EDWARD F. COLLADAY, OF WASHINGTON, DISTRICT OF COLUMBIA

REGIONAL SYSTEM OF RADIO BROADCAST DISTRIBUTION

Application filed February 9, 1924. Serial No. 691,824.

My invention relates to regional systems of distribution for radio broadcasting from a central station to subscribers' stations, and has for its object the production of a system in which secrecy may be maintained and improved reception of all stations assured. According to my invention, heterodyning is employed to secure improved receiving at substations as well as secrecy, and electric light 5 wires or the equivalent are employed for conveying the modulated waves to said substations, heterodyning waves being transmitted through the ether, or vice versa at will and interchangeably. My present invention is an improvement in the respect stated over inventions disclosed and claimed in my prior copending applications Serial No. 581,829, filed August 14, 1922, patented January 6, 1925, No. 1,522,357, and 667,024, filed October 20 6, 1923, patented March 9, 1926, No. 1,576,309. In respect to part of the subject matter, this application is a continuation in part of my application No. 667,024, and it is also related as a continuation in part to my prior application Serial No. 586,842, filed September 8, 1922, patented December 11, 1928, No. 1,695,171, jointly with James B. Hoge.

My invention is illustrated in the accompanying drawings, in which:

Fig. 1 is a diagram showing a combined electric light and radiophone system embodying my invention.

Fig. 2 is a diagram showing the connections at the central station and a subscriber's station.

Fig. 3 is a diagram showing the circuits at a subscriber's station, together with telephone connections to a central office, a portion of an electric light network, and a meter of convenient type.

Fig. 4 is a diagram showing a connection of the meter for registering time use.

Referring to the drawings, and particularly to Fig. 1 this shows an electric lighting system with a central power station C, five transformer substations, C', C², C³, C⁴, C⁵, consumers' mains M' fed from the substations, and feeder mains M, distributing the power from the main generating plant typified by G to the substations. At the central

station Sw indicates the usual main switchboard, and Sw' a supplemental switchboard for purposes to be described. From this board Sw' communication wires 35, 37, 39, 41 extend out to the substations, one pair or more accompanying each feeder cable in the ducts. At each substation a small switchboard Sw² is provided, equipped with an automatic selective switch 36, 38, 40 or 42, having a switch arm or wipers connected to the incoming line 35, 37, 39 or 41, and contacts over which the wipers are stepped in operation, to connect with local lines to consumers' radiophone stations. Thus at substation C' the switch 36 has contacts connected to wires 43, 44, which extend from that substation to the radiophone stations 43^a, 44^a. This same substation C' carries a feeder main M² to a second transformer station C⁵, and the accompanying communication wire 45 extends to a switch 46 at said substation, from which wires 47, 48 extend to radiophone stations 47^a, 48^a. This subdivision of the system requires an extra digit in the number transmitted from the central station C, the switches 34, 36, and 46 corresponding to first and second selectors and connectors in an automatic telephone system. No detail of the switching circuits or the operating mechanism of the automatic switches is given herein, as such circuits and switches are well known, and of themselves form no part of the present invention, the main features of which as regards the communication circuits, lies in the ability of the central office operator to automatically connect himself to any part of the system through the minimum number of wires, comprising in this case a single pair from the central station to each substation, and single pairs diverging therefrom to the further subdivisions of the system. The last link in any of these circuits is the individual drop wire, extending from a terminal box to the building in which current is to be used. These drop wires are relatively short, and I contemplate employing them for a double purpose, viz., for communication by phone or otherwise over the wires, and as antennas for the radiophone instruments, where found expedient or desirable. This will be described hereinafter.

Transformers K are the substation transformers, and transformer K' are the house or pole transformers feeding the consumption circuit M¹⁰ from the house mains M'. The consumption circuits M¹⁰ carry translating devices such as lamps L, and may also supply current to the radio telephone receivers RR, to be presently described. These radio telephones are all standardized and of uniform design and construction, and are calibrated and locked when installed, so as to operate on a common wave length only, i. e., the beat wave length due to heterodyning of waves of different frequencies received over the circuit M¹⁰ and through the ether, respectively. A transmitter RT may be located at the central power station or at some other point on the central power distributing system, and in any case, the switchboard Sw' will be located at the same point, and distribution over the communication circuits effected therefrom. Since the local radio telephone receivers RR are all uniform and fixed as to their tuning, any tuning required must be on the part of the transmitting operator at switchboard Sw', who is able to listen in and observe the operation of the outlying receiving instruments.

For supervision of the quality of reception, testing, etc., of a subscriber's radio receiver, and controlling the quality of reception, the operator at the central station C makes use of the telephone connections to be established through the automatic switching means and circuit connections indicated in Fig. 1 at 32, 34, 35, 36, and 43-44. For example, if the receiving set at sub-station 48^a is to be connected with, the operator at the central station first operates his dial 32 to step the switch 34 around into connection with line 35 leading to sub-central C', then dials again to extend the connection through switch 36 to line 45 leading to sub-central C⁵, and again operates his dial 32 to step the switch 46 around into connection with line 48, the individual drop line to station 48^a. Through the connection thus established the central station operator is enabled to listen in on the audio reproduction of the subscriber's receiver, which observation will enable him to determine what faults are present and the necessary remedies to be applied.

Referring to Fig. 2, the transmitting and receiving connections are shown in more detail than in Fig. 1 wherein relay radio transmitter RT is normally connected through suitable switch 60-60^a and coupler CC to the main distribution circuits M, preferably through the switchboard Sw. The switch 60-60^a can be thrown so as to connect the local oscillator OC in place of the relay transmitter RT. The second local oscillator OC' is used to radiate heterodyning waves to the substation receiver RR to balance against the wire guided waves from the transmitter

RT or the equivalent local oscillator OC. When the relay transmitter RT is receiving and distributing to the local subscriber, modulated waves from distant stations, the modulated waves are confined to the wires and the heterodyning waves from OC' can be unmodulated, which renders them imperceptible to any but subscribers. When the local oscillator OC is connected to the network in place of RT, since both component wave trains are locally originated at OC and OC' respectively, either one can carry the modulations, hence I have shown the local modulator LM adapted to be connected by switches 61-61^a and 62-62^a with either one of the local oscillator circuits at will and interchangeably.

In Fig. 2, RT represents the relay transmitter for distributing waves from distant stations, it being understood that they are amplified to any desired degree in passing through the relay transmitter RT. The symbols in Fig. 2 marked RT represent therefore a complete receiving, amplifying, and transmitting device, adapted to take modulated waves from distant stations and transmit them over the net work M'-M¹⁰. SC is the subscriber's coupler to his antenna SA, RR is his instrument as a whole, the receiving phone being shown at r. At the central station in Fig. 2, the coupler CC can be connected to the local oscillator OC while the companion oscillator OC' is connected through a coupling OC² to the aerial radiator OA.

In Fig. 3, the subscriber's station is further amplified. The coupler 28 and antenna 25^a are the same as in Fig. 2, but the connection from house mains M' is brought in through a plug P from which conductors are led to the heterodyning coupler coil which is shown inserted in the filament grid circuit of the detector tube. Since heterodyning is equivalent in its effect to one stage of audio amplification, and since radio amplification takes place at the central station C, I show one stage of audio amplification at the subscriber's station, and a loud speaker; but this is understood to be typical only, and head telephones may be used or any known or suitable arrangement of heterodyning circuits may be substituted for the audio portion of the circuit shown.

The meter shown in Fig. 3 is not claimed herein but consists of a Veeder counter or the equivalent with an actuating magnet adapted to be energized each time the set is put into operation. Instead of this arrangement of meter for registering the number of times the set is used, time of use may be registered if desired by substituting any known or suitable form of meter therefore, as for example that shown in Fig. 4, and in my prior application Serial No. 586,842 (Patent 1,695,171) hereinbefore referred to.

I claim:

1. In a regional distribution system for radio broadcast, a central station, a wired network extending therefrom to outlying points of consumption, and connected to all of said points in common, subscriber's radio telephone receiving instruments at said points of consumption, means at the central station for transmitting radio frequency waves over said wired network, other means at the same central station to radiate radio frequency waves through the ether, means at the central station for controlling the frequency relation between the two sets of waves such as to produce a given superaudio beat between them when combined, means at each subscriber's station to receive both of said sets of waves, one over the wired network and the other through the ether, with means to heterodyne the same through suitable detecting means so as to produce audio waves in a telephone receiver, said heterodyning and detector apparatus being tuned, calibrated and locked together with means at the central station for modulating one of said sets of waves, and means to apply the modulator to either one of the waves transmitters, at will. 70
2. In a system of radio broadcast distribution, a central station and subscribers' stations, a wired network interconnecting them, said network being common to all for the general distribution of electric currents, means at the central station for radiating modulated waves through the ether, means also at the central station for transmitting unmodulated waves through the wired network at a different frequency from the ether waves, means at the subscribers' stations for receiving through the ether and over the network respectively said two sets of waves, and for combining or heterodyning the same so as to produce a modulated and detectable beat waves, said means being permanently tuned, calibrated and locked against disturbance, together with means under control of the central station operator for reversing the mode of transmission of the respective wave trains, so as to radiate the unmodulated waves, and to transmit over the wired network the modulated waves, and other means under control of the central station for maintaining a constant difference in frequency between the two wave trains. 95
3. In a regional distribution system for radio broadcast, a central station, a wired network extending therefrom to outlying points of consumption, and connected to all of said points in common, subscriber's radio telephone receiving instruments at said points of consumption, means at the central station for transmitting radio frequency waves over said wired network, other means to radiate radio frequency waves through the ether, the frequency relation between the two sets of waves being such as to produce a superaudio beat between them, means for modulating one of said sets of waves, means at each subscriber's station to receive both of said sets of waves, one over the wired network and the other through the ether, with means to heterodyne the same through suitable detecting means so as to produce in a telephone receiver audio waves corresponding to the said modulations, said heterodyning means and the detector circuit being permanently tuned, calibrated and locked. 100
4. In a system of radio broadcast distribution, a central station and subscribers' stations, a wired network interconnecting them, said network being common to all for the general distribution of electric currents, means at the central station for radiating modulated waves through the ether, means also at the central station for transmitting unmodulated waves through the wired network at a different frequency from the ether waves, means at the subscribers' stations for receiving through the ether and over the network respectively said two sets of waves, and for combining or heterodyning the same so as to produce a modulated and detectable beat waves, said means being permanently tuned, calibrated and locked against disturbance, together with means under control of the central station operator for reversing the mode of transmission of the respective wave trains, so as to radiate the unmodulated waves, and to transmit over the wired network the modulated waves, and other means under control of the central station for maintaining a constant difference in frequency between the two wave trains. 90
